(57) **CLAIM**

The ornamental design for a docking station for a floor
cleaning machine, as shown and described.

DESCRIPTION

FIG. 1 is a front, top and left side perspective view of a
docking station for a floor cleaning machine showing the
new design;

FIG. 2 is a front, top and right side perspective view thereof;

FIG. 3 is a front elevational view thereof;

FIG. 4 is a left side elevational view thereof;

FIG. 5 is a rear elevational view thereof;

FIG. 6 is a right side elevational view thereof; and,

FIG. 7 is a top plan view thereof.

The broken line showing of various elements in FIGS. 3-6
forms no part of the claimed design.

1 Claim, 7 Drawing Sheets
